UNITED STATES PATENT OFFICE

DONALD A. CUMFER, OF NUTLEY, NEW JERSEY, ASSIGNOR, BY MESNE ASSIGNMENTS, TO THE PATENT AND LICENSING CORPORATION, OF BOSTON, MASSACHUSETTS, A CORPORATION OF MASSACHUSETTS

METHOD OF AND APPARATUS FOR PRODUCING ROOFING

Application filed July 17, 1929. Serial No. 378,878.

This invention relates to an improved method of and mechanism for treating roofing material and is designed particularly for use in connection with prepared asphaltic roofing of the type in which asphalt saturated 5 felted fibrous material is coated with weather and waterproofing material and surfaced with comminuted mineral matter.

An object of the invention is to provide 10 means for reprocessing previously prepared roofing of this character, with a view to enhancing the durability and attractiveness of the finished product, the reprocessing being designed to encase the exposed portions of 15 the roofing, including the edges as well as the surfaces thereof, in an envelope of weather and waterproof material, such for example as high melting point blown asphalt, within which may be partially embedded 20 mineral surfacing material of suitable character. The method and mechanism forming the subject matter of the present invention is adapted, for example, to the manufacture of roofing shingles of the character set forth 25 in the patent to L. Kirschbraun, No. 1,612,776, although it should be understood that the principles of the invention may be utilized in the manufacture of roofing material having only a single layer of coating and mineral 30 surfacing, as will clearly appear to those skilled in the art.

It is another object of my invention to provide for carrying on the operation of coating the roofing base with the layer of weather 35 and waterproof material while the base is moving in a direction parallel to the butt edges of the finished elements and for carrying on the subsequent operation for surfacing the base while the latter is moving in 40 a direction at right angles to the butt edges of the finished elements, the translation of the motion of the material from one direction of movement to the other taking place at a convenient point subsequent to the coating 45 operation and prior to the application of the mineral surfacing material upon the face of the roofing which is intended to be exposed.

The procedure as last described is of particular advantage in connection with the 50 production of roofing elements surfaced with

a plurality of colors such that when a number of the elements are assembled on the roof, a pleasing and harmonious effect will be secured. In order to produce the most desirable color effects, the practise is to surface the 55 elements, or the sheets from which they are severed, with differently colored bands of mineral grit, these bands being so applied as to run generally transversely of the butt edges of the completed elements. It will be appreciated by those skilled in the art that where the surfacing operation is conducted while the base is progressing through the machine in the direction in which the base travelled during the coating operation, viz, 60 in a direction parallel to the butt edges of the finished elements, it becomes exceedingly difficult to apply the surfacing material to the base in bands of different color running 65 at right angles to the direction of movement of the base, this problem becoming particularly acute in those cases where the coating material is applied only to the portion of the base which forms the exposed areas of the finished elements, for in such cases, rapid 70 commercial operation makes it necessary to apply the coating material to the base while the latter is moving in a direction parallel 75 to the butt edges of the finished elements.

The principles underlying my present invention, may be utilized in connection with the treatment of continuous lengths of sheet material from which separate elements are cut, as well as with elements that are pre-cut to desired size and configuration, and the description to follow will set forth embodiments of the invention in both of these aspects.

For a more complete understanding of the invention, reference is had to the accompanying drawings in which,

Figure 1 is a view in plan of a layout of apparatus that may be employed in carrying out the invention,

Figure 2 is a view in side elevation of the 95 apparatus shown in Figure 1,

Figure 3 is a diagrammatic illustration showing how the elements are transferred from the one direction of movement to the right angular direction,

Figure 4 is an elevation of the portion of the apparatus employed in the surfacing stage,

Figure 5 is a view in elevation of the forward end of the mechanism shown in Figure 4,

Figures 6, 7, 8, 9 and 10 are sections through Figure 2 along the lines indicated in the last named figures by corresponding numerals,

Figure 11 is a detail in perspective, showing the relation of certain parts of the structure,

Figure 12 is a plan view showing an arrangement for starting with continuous lengths of roofing base to be treated in accordance with the invention,

Figure 13 is a side elevation of the mechanism shown in Figure 12.

Referring first to Figures 1 to 11 inclusive, wherein is illustrated a method and an organization of apparatus for carrying out the invention in conjunction with precut elements, the numeral 10 indicates a table or other suitable support upon which a number of the precut elements may be stacked for feeding them directly to the machine, the elements themselves being indicated by the numeral 11. In carrying out the invention, I provide means for forcibly gripping the elements along the portions thereof which it is not desired to coat, so that they will be fed along continuously with these portions concealed, and the remaining portions, as for example, those portions which are to form the exposed areas of the elements, projecting outwardly from the gripping mechanism and free to receive the coating material as the elements are being fed in the direction of their butt edges. As shown, this feeding and supporting means comprises a pair of upper and lower endless belts 12 and 13 traveling around pulleys 14 and 15 respectively, the arrangement being such that the lower stretch of the belt 12 and the upper stretch of the belt 13 are spaced from each other a distance corresponding substantially to the thickness of the elements so that they will pinch or grip the elements and convey them at a uniform speed through the machine, the elements being gripped by the belts along their head portions as will be understood, so that the areas of the elements to be coated extend laterally outward of the belts in position to receive the coating material. The elements as thus gripped and supported by the belts preferably first pass over a heating chamber 16 for driving out moisture therefrom and to render them slightly warm and in condition for better retention of the coating material. The elements then pass beneath a stream or spray of coating material, such for example as molten blown asphalt of melting point 220° F., delivered from a suitable source of supply through the feed pipe

17. A screening device 18 may, if desired, be interposed between the elements and the discharge end of the feed pipe to collect any lumpy material that may exist in the coating, the coating material then flowing onto the

70

free upper face of the elements and over the butt and side edges thereof, as well as over the edges of all slots or notches that may be formed in these precut elements to define tabs or shingle-simulating portions therein. The

75

coating material may be doctored off to form a smooth layer thereon by means of the doctor roll 19. Similar coating may also, if desired, be applied to the free underface of

80

the elements as by means of a coating roll 20 revolving in a bath of the coating material 21, this undercoating being preferably also doctored as by means of a pipe 22. When coating material is applied to the underface

85

of the element, I preferably apply surfacing material to this coating prior to the application of the surfacing material to the upper face of the elements, which is intended to be the exposed face when the elements are laid on a roof. For this purpose, I provide an endless carrier belt 23 passing around suitable

90

pulleys 24, 24a, and 25, the arrangement of these pulleys being such that the upper stretch of the belt 23, moving in the direction indicated by the arrows, will first travel in an upwardly inclined direction from the pulley 24 to the pulley 25, and then assume a horizontal direction of travel from the pulley 25 to the pulley 24a. The driving

95

mechanism for this carrier belt is preferably arranged to drive the belt at the same linear speed as the belts 12 and 13. During the passage of the carrier belt from the pulley 24 to the pulley 25, surfacing material such as

100

crushed slate, powdered talc, mica or the like, is discharged thereon from a hopper 26 to which the surfacing material may be supplied from any convenient source as by means of a conduit 27. The bed of surfacing mate-

105

rial thus carried on the belt 23 will be contacted with the lower face of the elements at the upper horizontal stretch of the carrier belt, the surfacing material becoming partially imbedded in the coating on the lower face

110

of the element while surplus surfacing material drops into a receiver 28 as the belt passes around the pulley 24a, this surplus material being preferably returned in any convenient manner to the conduit 27. The heretofore

115

described mode of coating the roofing base provides a novel and inexpensive procedure for processing, through the coating stage, roofing elements of the type set forth in the aforementioned Kirschbraun patent.

120

After the elements have been thus coated on the upper face, or coated on both faces and surfaced on the underface thereof, and prior to the application of the surfacing material to the upper face thereof, the movement of the elements is converted from a direction

125

parallel to the butt edges thereof, into a direction at right angles to the line of the butt edges thereof. For this purpose, I provide a rotating spider wheel 30, or similar device, suitably driven in such relation to the drives for the belts 12 and 13 that the successive elements delivered from the discharge end of the gripping belts 12 and 13 will be received upon one of the arms 31 of the spider, which latter, rotating in a counterclock-wise direction as viewed in Figure 4, delivers the successive elements onto an endless feed belt 33 passing around suitable pulleys 34. In Figure 3 I have illustrated diagrammatically this translation of the movement of the elements from a direction parallel to the butt edges thereof to a direction at right angles thereto. The purpose of providing the spider, or similar device that may be used in lieu thereof, is to enable the elements to be discharged onto the feed belt 33 in a position with the butt edges of the elements substantially at right angles to the direction of travel of the belt 33, for otherwise the elements, in being discharged from the belts 12, 13, may fall upon the belt 33 with the butt edges thereof at various angles to the direction of movement of the belt. This would be undesirable in accordance with my invention since in order to surface the elements in the most desired manner, the different colors of surfacing material should be applied in bands running generally parallel to the side edges of the elements and at right angles to their butt edges. By thus interposing a receiving device such as the spider 30, proper alignment of the elements is had before their discharge onto the feed belt 34. It will be apparent also that where coating material is applied to the underface of the elements, this coating layer must be surfaced with mineral grit or the like prior to the delivery of the elements to the belt 33, as otherwise the coating material on the underface of the elements would cause them to adhere to the belt.

The elements thus properly positioned upon the belt 33, then pass beneath a surfacing device for applying surfacing material preferably in bands of different colors to the upper coated face thereof. This surfacing device may take the usual form of hopper 35 separated by partitions 36 into compartments 37, each of which may receive surfacing material of desired color from a conduit 38 individually to each compartment. The surfacing material will thus be discharged from the hopper 35 onto the coated elements in bands extending transversely of the elements, whereupon the elements may be fed between press rolls 39 for causing the surfacing material to be partially imbedded in and affixed to the coating. A suitable receiving or collecting device 40 is positioned adjacent the forward or discharge end of the belt 33 to

collect the elements and receive the surplus surfacing material, the latter being delivered from the lower end of the collecting device 40 onto a receiving belt 41, and conducted thereby to suitable elevators or other conveying devices for returning the surplus material, either as separate streams to the respective hoppers 37, or as a mixture to the conduit 27 to be applied to the underface of the elements.

Thus far I have described a method of carrying out my invention in conjunction with the treatment of precut elements, but as already stated, the principles of the invention are likewise applicable to a procedure wherein the starting material comprises continuous lengths of roofing.

In Figures 12 and 13 I have illustrated a procedure of the last mentioned type omitting from these figures, for the sake of clearness, some of the parts shown in Figures 1 to 11. In these figures, the starting material comprising continuous lengths of the base 45, is on the portions of the upper, or both faces thereof which are free of the belts 12 and 13, and surfaced on the lower coated face in the manner already described. The base is then passed through cutting mechanism 46 positioned between the discharge end of the belts 12, 13 and the rotatable spider wheel 30, for severing the continuous strips of material into separate elements, which pass onto the spider wheel 30 for delivery to the feed belt 33. The cutting mechanism 46 may comprise a lower bed roll 47 and an upper cutting roll 48 formed with blades for severing successive elements from the continuous lengths of the base 45, and also, if desired, with knives for forming slots or other tab-defining means in the exposed portions of the elements, the successive elements as already stated, being then delivered to the belt 33 to travel during the surfacing operation, in a direction at right angles to the direction of movement of the base 45 during the coating operation. In this procedure, the slots, or tab-defining portions, may, if desired, be formed along the free edge of the base 45 prior to the coating stage, the cutting cylinder 48 being then employed merely to sever the elements from the base prior to the transfer of the elements to the conveyor belt 33.

The operation of the apparatus heretofore disclosed is as follows:

The stacked roofing elements 10 to be treated are located adjacent one end of the machine and on the platform or table 11. These elements 10 are so inserted in a single file relation between the adjacent reaches of the gripping and conveying belts 12 and 13 that only the head portions of the elements are gripped thereby and the butt or portions to be exposed extend outwardly from the longitudinal extremities of these belts. As shown in Figure 1, the elements are conveyed in a horizontal plane with their butt edges

parallel to their line of travel and in this manner pass between the heating chamber 16 and the asphalt supply device 17 under which is located the screen device 18 adapted to separate the lumpy material from the fluid coating. The elements carrying the coating material discharged from the screen device onto the free or ungripped portions of the elements pass between the rolls 19 and 20, the roll 19 serving as a doctoring means for the coating on the upper face of the coated strip and the roll 20 carrying asphalt from the tank 22 and serving to coat the lower face of the elements. After the coating on the lower face is suitably doctored by means of the doctoring device 22, the elements continuing in their straight line travel have the coating on their lower faces surfaced with mineral grits carried by the belt 23. The coated elements while in their original position relative to the direction of travel of the belt and still continuing in the same direction are delivered from the discharge end of the gripping belt onto the transfer mechanism 30. The transfer mechanism 30 deposits the elements onto the moving belt 33 so that their butt edges are now substantially at right angles to the line of travel of the second conveying belt 33. The direction of travel of the conveying belt 33 is at right angles to the direction and line of travel of the first mentioned conveying mechanism 12 and 13. Thus the elements are maintained in a horizontal plane while being carried along by the conveyors 12 and 33, but are caused to "change front" by the transfer mechanism 30. During the conveyance of these elements on the belt 33, the coating on the upper face thereof is surfaced with mineral grits delivered from a single or multi-compartment hopper 35, and then pass between the press rolls 39 and finally into the receiving mechanism 40.

The operation will be substantially the same where the base is a strip of indeterminate length. With such a base the operations on the first conveying mechanism are the same. By means of the cutting mechanism 46 interposed between the discharge end of the belts and the transfer mechanism 30, the strip is severed into equi-length elements that are delivered to the transfer mechanism 30 which deposits the severed elements onto the conveyor belt 33. As the elements are conveyed on the belt 33, they may be treated in a manner similar to that already described.

Having thus described my invention it will be apparent to those skilled in the art that numerous variations and changes may be made therein without departing from the spirit of the invention as set forth in the appended claims.

I claim as my invention:

1. In the method of producing roofing elements, the steps which comprise coating the

roofing base while it is moving in a direction parallel to the butt edge of the finished elements and applying surfacing material to the coated portions of the base while it is moving in a direction at right angles to the butt edge of the finished elements.

2. In a method of producing roofing elements, the steps which comprise feeding a roofing base in a direction parallel to the butt edge of the finished elements, applying coating material to a surface of the base while being thus fed, translating the motion of the base to movement in a direction at right angles to the butt edges of the finished elements and while moving in the latter direction, applying surfacing material to the coated surface thereof.

3. In a method of producing roofing elements the steps which comprise feeding a roofing base in a direction parallel to the butt edge of the finished elements, applying coating material to a surface of the base while being thus fed, translating the movement of the base to a direction at right angles to the butt edges of the finished elements and while moving in the latter direction, applying surfacing material to the coated surface thereof in a plurality of bands of different colors.

4. The method of producing roofing elements surfaced in bands of different colors extending transversely of the butt edge of the elements, which comprises feeding the elements in a direction parallel to the butt edges thereof, applying coating material to a face of the elements while being thus fed, translating the movement of the elements to a direction at right angles to the butt edges thereof, and while the elements are moving in the last named direction, applying surfacing material thereto in bands of different colors extending transversely of the butt edges thereof.

5. The method of producing roofing elements surfaced in bands of different colors extending transversely of the butt edge of the elements, which comprises feeding the elements in a direction parallel to the butt edges thereof, applying coating material to both faces of the elements being thus fed, surfacing one of the coated faces of the elements, translating the movement of the elements to a direction at right angles to the butt edges thereof, and while the elements are moving in the last named direction applying surfacing material to the opposite face thereof in bands of different colors extending transversely of the butt edges thereof.

6. The method of producing roofing elements surfaced in bands of different colors extending transversely of the butt edge of the elements, which comprises feeding the elements in a direction parallel to the butt edges thereof, applying coating material to a portion of a face of the elements while being thus fed, translating the movement of the

elements to a direction at right angles to the butt edges thereof, and while the elements are moving in the last named direction, applying surfacing material thereto in bands of different colors extending transversely of the butt edges thereof.

7. The method of producing roofing elements surfaced in bands of different colors extending transversely of the butt edge of the elements, which comprises feeding the elements in a direction parallel to the butt edges thereof, applying coating material to a portion of both faces of the elements being thus fed, surfacing one of the coated faces of the elements, translating the movement of the elements to a direction at right angles to the butt edges thereof, and while the elements are moving in the last named direction, applying surfacing material to the opposite faces thereof in bands of different colors extending transversely of the butt edges thereof.

8. Apparatus for the purpose described, comprising means for feeding separate elements in a direction parallel to the butt edges thereof, means for supplying coating material to a face of the elements as thus fed, means for feeding the coated elements at right angles to the first named direction of movement, and means for surfacing the coated face of the elements while moving in the right angular direction.

9. Apparatus for the purpose described comprising means for feeding separate elements in a direction parallel to the butt edges thereof, means for supplying coating material to both faces of the elements as thus fed, means for surfacing one of the coated faces of the elements, means for feeding the elements at right angles to the first named direction of movement and means for surfacing the other coated face of the elements while moving in the right-angular direction.

10. Apparatus for the purpose described comprising means for feeding separate elements in a direction parallel to the butt edges thereof, means for supplying coating material to both faces of the elements as thus fed, means for surfacing one of the coated faces of the elements, means for feeding the elements at right angles to the first named direction of movement and means for surfacing the other coated face of the elements in bands of different colors while moving in the right-angular direction.

11. Apparatus for the purpose described comprising means for feeding separate elements in a direction parallel to the butt edges thereof, said feeding means comprising a pair of endless belts arranged to grip the elements along the head portions thereof and to leave the remaining portions thereof free of the belts, means for supplying coating material to one of the free faces of the elements, conveying mechanism positioned adjacent

the discharge end of said endless belts and having movement in a direction at right angles thereto, means for delivering the elements from said endless belts to said conveying mechanism and means for supplying surfacing material to the coated face of the elements in bands of different colors during the travel of the elements on said conveying mechanism.

12. Apparatus for the purpose described comprising means for feeding separate elements in a direction parallel to the butt edges thereof, said feeding means comprising a pair of endless belts arranged to grip the elements along the head portions thereof and to leave the remaining portions thereof free of the belts, means for supplying coating material to both free faces of the elements, means for surfacing one of the coated faces of the elements, conveying mechanism positioned adjacent the discharge end of said endless belts and having movement in a direction at right angles thereto, means for delivering the elements from said endless belts to said conveying mechanism and means for supplying surfacing material to the other coated faces of the elements in bands of different colors during the travel of the elements on said conveying mechanism.

13. In the art of producing roofing wherein felted fibrous material is coated with waterproof material and subsequently surfaced with comminuted mineral matter, the improvement which consists in the step of coating face to be exposed of the material while the material is moving in one direction relative to its butt edge and surfacing the material while it is moving in a direction substantially at right angles to the first named direction.

14. In the method of producing roofing, the steps which comprise gripping the roofing base in horizontal position along a widthwise portion thereof, feeding the base forwardly and applying fluid coating material to one surface of the ungripped portion thereof.

15. In the method of producing roofing elements, the steps which comprise gripping pre-cut elements in a horizontal position along portions of both faces thereof, feeding the thus gripped elements forwardly, and applying fluid coating material to the un-gripped portions of one face thereof.

16. In the method of producing roofing elements, the steps which comprise gripping pre-cut elements in a horizontal position along portions of both faces thereof, feeding the thus gripped elements forwardly, applying fluid coating material to the ungripped portions of both faces of said elements, and partially embedding comminuted surfacing material in the coated areas.

17. In apparatus for the purpose described, a pair of belts movable in an endless path and adapted to receive and grip a roofing

element in flatwise position therebetween to convey the element forwardly in a horizontal position with portions of element extending outwardly free of said belts, means for applying fluid coating material to one face of said free portions of the element as it is being fed forwardly by said belts, and means for surfacing the coated portion with comminuted mineral matter.

- 10 18. In apparatus for the purpose described, a pair of belts movable in an endless path and adapted to receive and grip a roofing element in flatwise position therebetween to convey the element forwardly in a horizontal position with portions of element extending outwardly free of said belts, means for applying fluid coating material to both faces of said free portions of the element as it is being fed forwardly by said belts, and means for surfacing the coated areas with comminuted mineral matter.

Signed at Rutherford, in the county of Bergen and State of New Jersey, this 16th day of July, A. D. 1929.

25 DONALD A. CUMFER.
